UNITED STATES PATENT OFFICE.

THOMAS B. MILLER, OF KANSAS CITY, MISSOURI.

MITER-CLAMP.

1,034,482.

Specification of Letters Patent.

Patented Aug. 6, 1912.

Application filed August 21, 1911. Serial No. 645,117.

To all whom it may concern:

Be it known that I, THOMAS B. MILLER, a citizen of the United States, residing at Kansas City, in the county of Jackson and 5 State of Missouri, have invented certain new and useful Improvements in Miter-Clamps, of which the following is a specification.

This invention relates to miter clamps 10 and is designed more especially as an improvement in the similar device on which I secured Patent No. 978,187, December 13, 1910, my special object in this connection being to provide means for more effectively 15 holding frames of different sizes in position while fastening the parts thereof together.

A further object is to produce a clamp of simpler and cheaper construction than the patented one referred to.

20 With these objects in view the invention consists in certain novel and peculiar features of construction and organization as hereinafter described and claimed; and in order that it may be fully understood reference is to be had to the accompanying 25 drawings, in which:

Figure 1, is a plan view of a miter clamp embodying my invention. Fig. 2, is a side view of the base of the clamp. Fig. 3, is a 30 front view of the base of the clamp. Fig. 4, is a section on the line IV—IV of Fig. 1 and shows a part of a picture frame in the clamp. Fig. 5, is a cross section on the line V—V of Fig. 1. Fig. 6, is a section on the 35 line VI—VI of Fig. 1. Fig. 7, is a detailed perspective view of a part of one of the clamping bars of the clamp.

In the said drawings, 1 indicates the base provided centrally with a channel 2 and 40 with a pair of forwardly-diverging channels 3 constituting branches at the front end of channel 2. The base is also provided at opposite sides of channel 2 with a pair of forwardly-diverging channels 4. The base 45 consists of a bottom plate and plates 5—5, 6—6, 7—7, 8 and 9—9 screwed as shown or otherwise secured to the bottom plate. The adjacent edges of plates 5 which are parallel, and the inner ends of plates 6, are 50 formed with grooves 10, and the inner edges of plates 7 are grooved as shown at 11, and

the rear edges of plates 6 are grooved as at 12.

13 are standards bolted to plates 5 at opposite sides of channel 2, and pivoted to 55 said standards is a cross bar 14, and to prevent the cross bar 14, from working freely in the standards, the latter are split as at 15 and clamping bolts 16 extend through them so that the split ends may be caused 60 to bear with an increased pressure on the pivoted bar when necessary.

17 is a threaded rod extending through bar 14 midway its length and swiveled at its front end at 18 in a forked clamp 19, the 65 said clamp being held against turning movement by fitting on a pair of guide bars 20 paralleling and disposed at opposite sides of rod 17 and secured rigidly at their rear ends to the pivoted cross bar 14, the arrangement being such that operation of the screw rod results in sliding the forked clamp forwardly or rearwardly, and when it is desired to adjust the forked clamp 70 vertically, the bar 14 will turn in the standards 13, it being noticed that the inner sides of the forked front end of the clamp 19 extend at right angles to each other.

21 is a block secured at the rear end of the channel 2, and extending through said 80 block is a threaded rod 22 provided with a hand wheel 23 at its rear end. The rod extends through and bears a threaded relation to a slide block 24 fitting in channel 2 and provided with tongues 25 engaging grooves 85 10, and said block is provided in its underside with a recess 26 wherein fits and are pivoted a pair of bars 27 which extend forwardly in channels 3 and at their front ends are provided with laterally-projecting portions 28 to bear against the opposite edges of plate 8. At their opposite sides the bars are provided at their front ends with laterally-projecting tongues 29 engaging the grooves 11, and secured upon the front ends 95 of the said bars 27 are right angle triangle shaped jaws 30, the hypotenuse sides of which are formed with teeth 31 which parallel and lie in the same horizontal plane as upwardly-projecting ribs 32 at the front 100 edges of plates 6.

In practice strips 33 of molding from

which a picture frame is to be made, are first mitered at their ends in the customary manner and are then placed upon plates 7 with their outer sides bearing against the 5 ribs 32. The operator then turns wheel 23 so as to move block 24 rearwardly and thus effects rearward movement of bars 27 until the toothed jaws 30 bear against the inner sides of said molding strips and clamp the 10 same firmly against said ribs, with their adjacent ends fitting squarely together. The forked clamp is then caused to engage the rear sides of the molding strips at their meeting ends, and as the rod 7 is turned, the 15 forked clamp presses firmly against said molding strips and thus guards against any possibility of the same tilting when they are nailed together, as hereinafter described.

The nailing may be accomplished by hand 20 but preferably I will employ a nailer of the following construction. 34 is a plate bridging the channel 4 between a pair of plates 6 and 9 and resting upon the said plates, and said plate is provided with a depending cross 25 piece 35 having a tongue 36 engaging groove 12 of said channel, so that the said plate may be shifted along the length of said channel 4. The plate is provided with a pair of upwardly-projecting lugs 37 and extending 30 between said lugs and at right angles to ribs 32, is a rack bar 38 having an attenuated front end 39 disposed in a plane slightly above that of the ribs 32. 40 is a lever pivoted at 41 to and between lugs 37 and 35 provided with a segmental toothed head 42 engaging the rack bar, so that as the lever is drawn rearwardly the rack bar will be moved forwardly, opposite movement of the lever reversing the movement of the rack 40 bar.

The plate is provided with a channeled extension 43 to bear against the outer side of the adjacent rib, and resting upon said extension is a pair of guide blocks 44 which 45 abut together and in their abutting faces are provided with grooves 45 forming a receptacle for a nail as shown, the nail being disposed in longitudinal alinement with the attenuated end of the rack bar, and said 50 nail is held reliably in position by means of a pair of springs 46 secured at their rear ends to the sides of the extension 43 and at their front ends to the blocks 44.

Assuming that the molding strips are held 55 firmly together and that a nail is held between the blocks 44, the operator simply throws the lever rearwardly and thus effects the advancement of the rack bar and causes the same to engage the head of the nail and 60 force it forwardly between the blocks and through one of the molding strips and into the mitered end of the other so as to fasten the strips together, it being understood that the movement of the rack bar

continues until its front extremity has 65 slightly embedded the head of the nail in the adjacent molding strip. If the frame is a heavy one, the nailing attachment can be slipped out of the groove which it occupied in operating the nail and into 70 the corresponding groove at the other side, so that a second nail can be caused to assist in securing the two molding strips together, it being understood that the nails will thus 75 occupy intersecting planes.

From the above description it will be apparent that I have produced a miter clamp embodying the features of advantage enumerated as desirable, and it is to be understood that I reserve the right to make such 80 changes in the form, proportion, detailed construction and arrangement of the parts as properly fall within the spirit and scope of the appended claims.

I claim:

1. A miter clamp, comprising a base provided with upwardly-projecting obliquely-extending ribs, movable jaws paralleling said ribs and adapted for clamping two strips against said ribs and abutting together endwise, a vertically swinging fork facing toward said jaws, and means for imparting longitudinal adjustment to said fork to cause it to approach or recede from said jaws.

2. A miter clamp, comprising a base provided with upwardly-projecting obliquely-extending ribs, movable jaws paralleling said ribs, and disposed within the angle inclosed thereby, a suitable support exterior 100 to said ribs, a rod adapted for longitudinal and vertical swinging movement with respect to and carried by said support, a fork swiveled upon and adapted to move longitudinally and swing with said rod, and means 105 adapted to swing with said rod and fork and bearing a sliding engagement with the latter to prevent lateral tilting movement thereof.

3. A miter clamp, comprising a base provided at opposite sides of its longitudinal center with upwardly-projecting obliquely-extending ribs, movable jaws paralleling said ribs and adapted for clamping two strips against said ribs and abutting together endwise, a suitable support, a bar carried by and adapted to rock on said support, a screw rod extending adjustably through said bar and disposed in the longitudinal plane of said base, a fork facing toward said jaws and swiveled to said screw rod, and guides paralleling said screw rod and secured rigidly to said cross bar and slidably connected to said fork to prevent lateral tilting movement thereof.

4. A miter clamp, comprising a base provided with upwardly-projecting obliquely-extending ribs, movable jaws paralleling

said ribs and adapted for clamping two strips against said ribs and abutting together endwise, standards mounted upon the base, a cross bar pivotally carried by said standards, a pair of parallel guide bars projecting from and carried by said cross bar, a forked clamp mounted slidably on said guide bars, and means carried by the cross

bar for effecting forward or rearward adjustment of the forked clamp.

In testimony whereof I affix my signature, 10
in the presence of two witnesses.

THOMAS B. MILLER.
